UNITED STATES PATENT OFFICE.

WALTER JACKSON, OF LEICESTER, ENGLAND, ASSIGNOR OF ONE-HALF TO
ALFRED ARTHUR JONES, OF SAME PLACE.

STITCH-WHEELING MACHINE.

SPECIFICATION forming part of Letters Patent No. 625,303, dated May 16, 1899.

Application filed January 16, 1899. Serial No. 702,288. (No model.)

To all whom it may concern:

Be it known that I, WALTER JACKSON, a subject of the Queen of Great Britain, residing at Leicester, England, have invented certain new and useful Improvements in Stitch-Wheeling Machines, (for which Letters Patent have been applied for in Great Britain, No. 11,624, dated May 23, 1898,) of which the following is a specification.

This invention relates to stitch-wheeling machines for use in the manufacture of boots and shoes, and has special reference to the type of machine in which the stitch-wheel is reciprocated to and fro horizontally when performing the stitch-wheeling operation.

The invention comprises certain improvements in the construction of the machine, all of which are hereinafter fully set forth, and specifically indicated in the claims at the end of this specification.

Referring to the accompanying drawings, Figure 1 is a plan of a stitch-wheeling machine constructed in accordance with this invention. Fig. 2 is a view, partly in side elevation and partly in vertical section, of the machine with the lower part of the standard and pedal connections omitted. Fig. 3 is a central vertical section of the work-support and its adjustments. Fig. 4 is a detail of the eccentric, connecting-rod, and reciprocatory tool-carrying slide.

A represents the standard of the machine, at the upper end of which is a table A', secured thereto by screw-bolts A². At one end of the said table there are bearings A³ A⁴, in which is located the driving-shaft B, carrying on one end a driving-pulley B', the boss of which extends to close against the bearing A³, and on the other end a collar B², screwed thereon and flush with the bearing A⁴, so that any endwise movement of the said shaft is obviated. Centrally on the said shaft is an eccentric B⁵, embraced by the split boss or bearing-plates of a connecting-rod C, the two parts C' C² of the said split boss which surround the eccentric being connected together by screws C³ with tightening-nuts C⁴ on their ends. The other end of the connecting-rod is provided with two bosses or knuckles C⁵, having a space between them to receive a

knuckle D' on the end of the tool-carrying slide D, which is located in the same plane as the shaft B and is reciprocated transversely or at right angles to the axis of rotation of the latter, thereby securing a direct action 55 and a smooth and even working of the slide. A pin E passes through each of the three knuckles C⁵ C⁵ D', thus uniting the slide and connecting-rod together, and the said pin is fixed against movement by a set-screw E', 60 bearing thereon and passing through the slide-knuckle D'.

Each of the two bosses or knuckles C⁵ of the connecting-rod is split transversely, as shown most clearly in Fig. 4, and has a clamping-screw C⁶ passing through, so that by tightening the said screws any wear or shake on the connecting-pin or bosses can be taken up and remedied.

The slide D has dovetailed sides and is 70 movably located between two guide-blocks F with correspondingly-shaped adjacent sides and fixed in position by screws F' G', passing through them into the table A'.

The guide-plate F is fixed flush up against 75 a rib A⁵, forming an integral part of the table A', and set-screws A⁶ pass through the said rib and bear against the said guide-bar to further lock the latter against movement. On the upper face of the slide is an internally-threaded boss D², Fig. 2, into which is screwed 80 a threaded stalk H. The head or enlarged upper end H' of the latter is cut away vertically for part of its thickness and depth to form a concavity H² to receive the curved 85 end of a lug or downward extension J' of the tubular tool-carrier J, which lug is fixed in the concavity and to the side of the said head by a screw-bolt J², Fig. 2, and nut J³, Fig. 1.

In each end of the carrier J there is located 90 a tubular socket or bush fixed in position by set-screws J⁴ and forming bearings for the freely-revoluble shank or spindle K, upon the end of which the boss of the milled-edged stitch-wheel tool L is fixed by a screw L'.

The angle of the tool-carrier and its tool may be varied by releasing the screw J², and the vertical adjustment of the same may be effected by rotating the screwed stalk H in the boss D². A set-screw H³, passing through 100

the boss and bearing against the stalk, fixes the tool in the vertical position determined upon.

M represents the freely-revolute work-support upon which the edge of the boot or shoe sole is placed to be operated upon by the stitch-wheel.

The work-support may have either a circular or a mushroom head (the latter being shown in Figs. 2 and 3) provided with a tubular shank M', fitting rotatably over the upper end of a pin N, furnished with a shoulder or integral collar N', upon which the said shank rests. The lower part of the said pin enters into the tubular end of a vertical spindle O and will be supported therein when its collar N' rests on the upper end of the spindle.

The work-support may be adjusted vertically and relatively to the tool L for varying thicknesses of soles by raising the shouldered pin in its socket and fixing it by a set-screw N², which passes through the latter for that purpose.

25 The spindle is located within a sleeve P, which passes downward through an opening in the table A' and is furnished with integral flanges P', which are attached to the table by bolts P². The lower end of the spindle is reduced in diameter and encircled by a spiral spring P³, compressible between a shoulder (formed by a reduction of the spindle) and the floor of the sleeve P, the said floor consisting of a short tubular threaded shank 30 or sleeve Q, fitting within the sleeve and provided with lugs Q', similar to a wing-nut, by tightening or releasing which the power of the spring can be correspondingly altered.

The spring tends to force the work-support 40 upwardly toward the stitch-wheel tool; but the movement of the work-support either upward under the influence of the spring or downward as the result of depressing a foot-pedal, as hereinafter mentioned, is limited by

45 shoulders O² O³, forming the extreme ends of a flat O⁴, formed on the spindle abutting against the end of a set-screw O⁶, passing through the sleeve P, locked in position by the lock-nut O⁵.

50 The lower end of the spindle O has connected thereto a rod R, whose opposite end is attached in any suitable manner to a foot-pedal of well-known construction, by depressing which the spindle and work-support can 55 be lowered.

By arranging the reciprocating tool-carrying slide D and its actuating mechanism all in the same or approximately the same plane a much smoother action of the slide is obtained than would otherwise be possible and there is not the same tendency for the slide to work loose and shake in its guides, the effect of which would be to impart such an amount of vibration to the stitch-wheel as

65 would be detrimental to its proper function.

It is important to note that by arranging the reciprocating slide D, shaft B, and connecting-rod C as set forth, whereby these parts operate in the same or substantially the same horizontal plane, I avoid the excessive friction between the slide and its guides, which would be caused were the operating mechanism arranged beneath the slide and operating upon the latter as in my British Patent No. 23,900 of 1896, such excessive friction having been found by me in practice to result in the slide becoming loose, and the tool is therefore not kept with a uniform pressure on the work and the stitch-wheeling is imperfectly performed. Although I prefer to employ the described means for operating the slide, yet I do not wish to be restricted to the exact construction and arrangement of such means, as any other means which will operate in the same or substantially the same horizontal plane with the slide may be employed.

The operation of the machine is as follows: The operator places his foot upon and depresses the pedal, which thereupon lowers the work-support M. The boot-sole is then placed tread-surface downward upon the latter, and upon the operator removing his foot from the pedal the spring P³ raises the work-support, which thereupon clamps the marginal edge of the sole between it and the tool L. The operator then moves the boot to and fro, and the frictional contact of the tool upon the edge of the sole adjacent to the upper produces a successive series of indentations upon the said sole edge and also rotates the tool. The reciprocating motion of the tool derived from the slide also tends to deepen and burnish the impressions or indentations made on the sole edge.

Having now particularly described and ascertained the nature of my said invention and in what manner the same is to be performed, I declare that what I claim is—

1. In a stitch-wheeling machine, the combination with a work-support, of a rotary tool, a carrier therefor, a reciprocating slide having a threaded boss, a threaded spindle on the carrier screwed within the said threaded boss and adapted for vertical adjustment therein, and mechanism for actuating the said slide.

2. In a stitch-wheeling machine, the combination with a rotary tool and its carrier and means for reciprocating them in a horizontal plane, of a work-support M, a shouldered pin N N' on which the latter is revolvably carried, a spring-controlled spindle O supporting the said pin the latter being adapted for vertical adjustment relatively to the spindle O, a sleeve P containing the said spindle and the spring, a foot-pedal and connections between the spindle and said foot-pedal for lowering the work-support relatively to the stitch-wheel.

3. In a stitch-wheeling machine, the com-

bination with a rotary tool and its carrier, and
means for reciprocating the latter in a horizontal plane, of a work-support M, shouldered
pin N, spindle O, sleeve P, and screwed sleeve
5 Q for adjusting the tension of the spring P³
substantially as and for the purpose de-
scribed.

In testimony whereof I have hereunto set
my hand in the presence of the two subscrib-
ing witnesses.

WALTER JACKSON.
